UNITED STATES PATENT OFFICE.

WILLIAM C. MCCOY, OF WILKINSBURG, PENNSYLVANIA.

ORE CONCENTRATOR.

1,423,130.

Specification of Letters Patent. Patented July 18, 1922.

Application filed September 26, 1917. Serial No. 193,230.

To all whom it may concern:

Be it known that I, WILLIAM C. McCoy, a citizen of the United States, and a resident of Wilkinsburg, in the county of Allegheny and State of Pennsylvania, have invented a new and useful Improvement in Ore Concentrators, of which the following is a specification.

My invention relates to ore-classifying machines and particularly to machines employing an oscillatable table for separating ores in accordance with their specific gravities.

One object of my invention is to provide a portable machine of the above-designated character which shall be very compact, have a large capacity, and shall require but little power for its operation.

Another object is to effect the greatest economy of water in the separation of the ores.

Another object of my invention is to provide such a movement of the ore-carrying parts of the machine that the most complete separation of the valuable metal-bearing particles of the ore from the worthless gangue may be effected.

A further object of my invention is to provide means for adjusting both the amplitude and period of vibration of the above-described movement through a wide range and also to adjust the natural period of vibration of the oscillated part.

A further object of my invention is to provide means for disturbing a substantially greater depth of the ore pulp at one end of the table than at the other.

A further object of my invention is to provide an engine for operating my device which will give the proper adjustable movement.

Such ore-classifying machines of the above-designated class as have heretofore been proposed have been of the so-called "Wilfley" class, which move the ore pulp along the surface of the concentration table by inertia; and of the "Vanner" type, in which the mineral is caused to settle by reason of its superior specific gravity and is caught on a moving belt or surface. The "Wilfley" tables give a very accurate separation of the various mineral-bearing ores in clearly stratified zones. The capacity of such tables is, however, relatively limited by reason of the necessity of moving each particle of mineral-bearing ore across the entire table by a succession of quick jolts

or blows in order to effect the separation. Whereas in concentrators of the "Vanner" type, to which the present invention belongs, the materials of a specific gravity greater than a certain value, settle and are collected upon the moving belt or table and, since each particle must settle only a distance of two or three inches, the capacity of this type of machine should be theoretically very large in comparison with the "Wilfley" class of table.

In both of these classes of concentrators, the ore-classifying table has heretofore been oscillated by some form of drive in which the speed of vibration is determined by the source of power and therefore is forced and out of harmony with the natural period of vibration of the table. Although this form of jolting motion is very effective where the movement of the ore particles is effected by the successive jarring or jolting of such particles, in concentrator tables of the "Vanner" class a jolting or jarring motion of the table disturbs the ore particles to such a degree that a thorough and effective separation of the ore from the gangue is very difficult to effect. This forced movement furthermore gives rise to very rapid and destructive wearing away of the moving parts, an undue consumption of power, and difficulties in maintaining the concentration belt in its proper position on the driving pulleys.

In accordance with my invention, I provide means for imparting a harmonic oscillation to the ore-carrying table which is controlled by the movement of the table and is of substantially the same period as the natural time of vibration of the table. Such a motion tends to lubricate the particles of material to be treated by partially suspending the same in the immersing fluid without greatly disturbing the fluid and thereby insures a thorough and complete separation of the heavier mineralized ore particles from the lighter weight gangue.

I furthermore contemplate the use of a resilient device for connecting the operating motors to the oscillated table in order to minimize the transmission of sudden jars or disturbing impulses to the table.

I have also found it necessary to provide a new form of operating engine in order to obtain the desired adjustable movement.

Fig. 1 of the accompanying drawings is a perspective view, with certain parts broken away and other parts shown diagrammati-

cally, of an ore concentrator embodying my invention; Fig. 2 is a side elevational view, shown in section, of a concentrator diagrammatically illustrated in Fig. 1; Fig. 3 is 5 a sectional end view of the concentrator taken substantially on the line 3—3 of Fig. 2; Fig. 4 is a sectional view of one of the fluid motors for operating the concentrator; Fig. 5 is a detail plan view of a relay 10 embodied in the concentrator; Fig. 6 is a sectional end view of the general arrangement of parts of a modification of the concentrator shown in Figs. 1, 2 and 3; Fig. 7 is a sectional view of the modified form of operating mechanism for controlling the movement of the concentrator shown in Fig. 6; Fig. 8 is a bottom plan view of the valve 15 shown in Fig. 7; Fig. 9 is a side-sectional view of the valve shown in Fig. 7; Fig. 10 is a diagrammatic assembled view of the 20 valve and the operating mechanism therefor; Fig. 11 is a side elevational view, shown partially in section, of the valve gear illustrated in Fig. 10; Fig. 12 is a view on the 25 line IX—IX of Fig. 11; Fig. 13 is a plan view of a portion of the ore-receiving surface; and Fig. 14 is a sectional view on the line XI—XI of Fig. 13.

Referring particularly to Figs. 1, 2 and 30 3 of the drawings, my invention comprises a tank 1 that is adapted to contain water, or other liquid, an ore-receiving table 2, that is oscillatably mounted within said tank and is adapted to be partially or wholly sub- 35 merged in said liquid, a hopper 3 that is adapted to supply material to the surface of the table 2, a conveyor 4 for removing the gangue from the tank of the concentrator, and a hopper 14 that is adapted to collect 40 the mineral-bearing ore.

The ore-carrying table 2, which I propose to employ embodies a frame 5 which is mounted upon two vertical springs 6 by means of bolted clamps 7, and which carries 45 a plurality of drums 8 that are rotatably mounted at the respective ends of the frame 5, and a belt 9 that extends around the drums 8. The term "table 2" will hereinafter refer to the assembled frame 5 and the belt 9 as a 50 unitary device.

A rigid framework 10 extends around the interior of the concentrator tank 1, to which it is rigidly secured, and provides saddles 11 for securing the bottoms of the vertical 55 springs 6 and a base upon which to mount fluid motors 12 for oscillating the ore-receiving table 2 by swinging the upper ends of the vertical springs 7 from side to side.

The upper ends of the springs 6 are connected by a rigid strut 13 to which the operating motors 12 are connected. The hopper 3, only a part of which is shown, is adapted to receive and distribute the material to be treated across the surface of the 60 belt 9.

The belt 9 has a plurality of riffles, or ore-collecting pockets as illustrated in Fig. 13 and which will be described later in detail, and is adapted to be driven in the direction of the arrow by some suitable driving connection, preferably through one of the drums 8, such for instance as the worm gear mechanism 15, or equivalent means. The table 2 is, furthermore, provided with a plurality of longitudinally positioned strips or 70 barriers 16 that are pivotally secured at their upper ends to a bracket 16^a that is rigidly mounted on the sides of the tank and secured at their lower ends to the oscillatable table. A plurality of similar barriers 17 extend longitudinally along the belt 9 and are adapted to be vibrated therewith by means of suitable connections 18 and 19. The strips 16 are each pivotally mounted upon to a laterally extending support 20 75 which is, in turn, secured to the tank 1, thus providing a plurality of barriers which vibrate with the belt 9 at their lower ends and which are pivotally mounted on the rigid support 20 at their upper ends. The barriers 17 are spaced more widely apart at 80 their lower ends in order that the gangue carried by the table will not become lodged between the barriers. These latter barriers provide a means for disturbing a substantially greater zone of the submerging liquid 85 over that portion at the table 2 which carries the greatest depth of ore.

The motors 12 for oscillating the table are preferably of a diaphragm type in order 90 that frictionally engaging parts may be avoided. Each of the motors comprises a metal bowl 21 to which a concentrically corrugated diaphragm 22 is secured. The bowls 21 are securely mounted upon the 95 framework 10 and have fluid-supply pipes 23 and 23^a communicating therewith. The diaphragms 22 are operatively connected to the strut 13 by means of the arms 24 and 24^a which are secured to said strut by means 100 of bolts 25 that respectively extend through a slot in the arms 24 in order to adjust the 105 distance between the points of connection to the diaphragms.

It should here be noted that the oscillating 110 motion for the table 2 is obtained by swinging the upper ends of the vertical springs 9 in order to avoid, to as great a degree as possible, the transmission of blows or jolts 115 to the oscillated table 2 which might result if the operating motors 12 were rigidly connected to the table. This relation of the 120 motors and the table however, gives rise to a difference in the phase of vibration of the 125 motors 12 and the table 2 which must be compensated for in order to definitely control 130 the movement of the table 2 and to maintain the motion uniform and without excessive jolting. In order to effect this compensation and to control the operation 130

of the motors 12 in accordance with the period of vibration of the table 2, I provide a valve 26, which is shown in diagrammatic sectional view in Fig. 1, that operates to admit fluid under pressure to one of the motors while exhausting the fluid from the other motor. The passageways 29 and 30 extend respectively to the right and left-hand motors, and the passageways 31 and 32 respectively constitute supply and exhaust ports which are alternately connected to the passageways 29 and 30 by the movement of the valve part 33. The operation of the valve part 33 is controlled by a magnet coil 34 that is energized from a battery 35 in accordance with the operation of a relay 36. The structure of the relay 36 is shown in substantially full size in Fig. 2. A light metal frame 37 is provided with a pair of ears 38 in which a screw 39 is rotatably mounted and is adapted to be turned by the knurled head 40. The adjustable stops 41 are engaged by the screw 39 and are moved equal distances in opposite directions by the operation of the head 40. This movement is the result of threading the halves of the screw 39 in opposite directions. The frame 37 is also provided with a spring 42, the function of which will be later described. The frame 37 is adapted to slide upon a support 43. A contact arm 44 is pivotally mounted on the support 43 by a pin 45 and is adapted to engage a contact member 46 to energize the coil 34. A leaf spring 47 is secured to the arm 44 by means of the members 48 and is adapted to engage the stops 41 in order to open and close the contact members 44 and 46. A stop 49 is provided for limiting the movement of the contact arm 44. A steel wire 50, which is held taut by a spring 51, is connected to the movable table 2 and the frame 37 and serves to transmit the movement of the table 2 to the frame of the relay 36. The spring 42 frictionally engages the contact arm 44 and drags the contact arm in the direction of movement of the frame 37.

Fig. 5 shows the relay 36 substantially at the center of its down stroke. Since the frame 27 is moving downwardly during the corresponding direction of movement of the table, the spring 42 frictionally engages the contact arm to drag the arm downward against the stop 49 and thus maintain the contact open and the valve 26 in the position to supply compressed air or steam to the right hand fluid motor 22. The movement of the table toward the left, as viewed in Fig. 1, continues until the stop 41 engages the end of leaf spring 47 which moves the arm 44 in opposition to the frictional drag of spring 42, to close the contact between the contact arm and contact member 46. When this contact is made, the valve 26 is energized and the fluid motors 22 swing the top

of the supporting springs to the right. These springs therefore oppose further movement of the table in the left hand direction but do not instantly stop such motion since the momentum of the table and the resiliency of the supporting springs permit the table to swing slightly beyond the point of reversal of the motors. Any continued motion of the table, however, merely flexes the spring 47 of the relay to more definitely hold the contact points together. When the reverse movement of the table begins in response to the flexed supporting springs 6, the tops of which were swung to the right when the valve 26 was energized, the movement of the relay frame 37 is also reversed and the drag of the spring 42 maintains the contact points together during the return swing of the table. When the table reaches a predetermined point in its return swing, the lower stop 41 engages the spring 47 to open the relay and thus deenergize the valve 26. This operates the motors to again swing the tops of the springs to the left. The operation of the motors therefore maintains an extremely uniform swinging of the table from side to side.

Since the stops 41 engage the spring 47 of the relay when the table occupies a predetermined position, the movement of the table can be accurately controlled. If an increased period of vibration is required for the treatment of a specific type of ore, the fluid pressure may be increased by adjusting the throttle valve 52. The adjustment of this valve governs, to a limited degree, the period of vibration of the table 2, by forcing the same slightly from its natural period of vibration. To effect a greater change in the period of vibration than can be obtained by the adjustment of the valve 52, a set of adjustable blocks 53 are provided which change the effective length of the springs 6 to alter the natural period of vibration of the table.

In order to operate my concentrator, the tank 1 is first filled with sufficient water to submerge the greater portion of the table 2. The belt is slowly operated in the direction of the arrow by the worm gear 15, and the table is oscillated from side to side by opening the throttle valve 52 which admits compressed air or steam to the motors 12.

The material to be treated is then fed into the hopper 3 at a prescribed rate. The smooth and uniform swinging motion of the table tends to maintain the particles of mineral in suspension within the submerging liquid, and thereby permits a very complete stratification of the treated particles in accordance with their specific gravities. The completeness of this separation depends upon the smoothness of movement of the concentrator table 2, since any irregularity of movement of undue disturbance of the

immersing liquid causes the gangue and heavier mineral-bearing ores to become mixed together and thus to defeat the purpose of the machine.

5 The oscillation of the concentrator table in accordance with its natural period of vibration has never before been employed in concentrators of this type and it has been found by actual operation of such a device 10 that the peculiar wave action resulting from this harmonic vibration of the concentrator table, produces a very effective separation of the heavier particles of ore from the lighter particles. The change in the character of 15 separation that is effected by adopting this harmonic vibration of the table may be caused by a peculiar wave action of the water on the submerged ore when the table is oscillated, or it may be that the total absence of jolting or jarring of the ore table 20 and the even uniform oscillation or lateral swinging of the table maintains the ore particles freely suspended in the submerging water and thus allows the heavier particles a 25 greater freedom to settle to the bottom of the mass of ore being treated.

Attention should, at this point, be directed to the baffles 17 that are positioned over the lower portion of the belt to which the gangue 30 gradually settles and which is covered to a much greater depth with the material being treated than the upper portion of the belt. The baffles 17 serve to disturb a greater zone of the immersing liquid over this portion of 35 the belt. The barriers 16 give a greater or less degree of disturbance to the liquid immediately over the belt 9, in accordance with their areas and their distance from the surface of the belt, by confining the disturbance 40 of the liquid to a relatively small zone. This serves to thoroughly wash the concentrates before they are deposited within the hopper 14.

45 A special form of riffle, which has been found to give satisfaction, is shown in Fig. 10. The novel feature of this riffle is that the points 55 of the crescent extend upwardly a much greater distance than the base 56 of the pocket, thereby creating a greater disturbance of the immersing liquid at a point 50 where the most gangue would be caught with the concentrates and to reduce, as much as possible, the disturbance at the place of repose of the heavier particles, which is at the base 56 of the pocket.

55 For certain ores, a greater or less degree of severity of motion is required in order to effect the suspension of the material to be treated within the liquid. This may, at times, 60 even approach a forced vibration, although the actuation of the table must at all times be maintained in accordance with the movement of the table in order to avoid churning or mixing of the material to be concentrated. 65 Such an action is secured by increasing the

pressure of the fluid or steam that is supplied to the motors 12 by means of the throttle valve 52, or by changing the natural period of vibration of the table 2 by changing the position of the adjustable blocks 53, 70 as hereinbefore described. By means of the latter adjustment, a very large change in the period of vibration of the table 2 may be effected. The wheel 40 provides a very sensitive and accurate means for adjusting the 75 amplitude of vibration.

It should also be noted that the table 2 may be moved pivotally around the bolt 7 by loosening the same in order to provide means for changing the angle of inclination 80 of the table for materials having different angles of repose. An arm 57 and the accompanying rack 58 provides means for assisting in the adjustment of the inclination of the table. It is essential, however, that 85 the table 2 be rigidly secured to the springs 6 by tightening the bolts 7 after adjustment is once made, in order to avoid all irregularity of movement.

90 The remaining figures of the drawings illustrate a modification of my invention wherein the fluid-controlling valve is directly connected to the moving table in order to avoid the use of the electromagnetic valve shown in Fig. 1. For this modification of 95 my invention, I provide a slide valve 60 which is shown in detail in Figs. 7 to 10 inclusive, and which is adapted to alternately connect the passageways 80 and 81, which respectively extend to the fluid motors to the supply pipe 82 in accordance with the position of the valve. The passageways 80 and 81 are also alternately connected to exhaust ports 83 by the movement of the valve. The movement of the valve 60 105 is limited to the smallest movement of the table that is desired by means of stops 61. The valve 60 is furthermore provided with clutches 62 for frictionally engaging one arm of a rod 63 for a purpose to be herein-after described. A toggle joint 64 is provided for imparting a motion to the vertically extending rod 65 that is an equivalent of the motion of the table 2 in both amplitude and period of vibration. A link 66, 110 which is pivotally mounted at a point 67, is connected to the valve 60 by means of a pin and slot arrangement 68 and is provided at its other end with a spring 69, which is gripped within a saddle 70 and which surrounds the other arm of the rod 65. A plurality of adjustable stops 71 are provided for engaging the respective ends of the spring 69 and actuating the valve 60 against its frictional engagement with the rod 65 115 to the reversed position when the rod 65 travels farther than a predetermined distance. By this means, the distance of travel, or amplitude of the swinging table 2, can be accurately adjusted and controlled during 120 125 130

the operation of the machine. Fig. 11 illustrates, in greater detail, the device for adjusting the position of the stops 71. The upper portion of this arm of the rod 65 is 5 hollow and is provided with a longitudinal slot 72 through which a tongue 73, that is provided on the stops 71, extends and engages a screw-threaded rod 74 that is rotatably mounted within the hollow portion 10 of the rod 65 and is adapted to be turned by a hand wheel 75. The upper and lower portions of the screw 74 are threaded in opposite directions in order to simultaneously move the stops 71 equal distances, in opposite directions, relative to the neutral position. A turnbuckle 76 is interposed in the rod 65 for adjusting the position of the stops 71 in accordance with the position of the table 2 when the same is at rest.

20 Although I have illustrated my invention as applied to a machine for separating mineral-bearing ores from gangue under a body of substantially stationary liquid, it should be understood that the exact type of 25 concentrator, with which my invention is employed, may be altered without departing from the spirit and scope of my invention. I desire, therefore, that only such limitations shall be imposed as are indicated in the 30 appended claims. The worm gear mechanism 15 and the table adjusting arm and racks 57 and 58 form no part of my present invention and are, therefore, specifically disclaimed as a portion of this invention.

35 I claim as my invention:

1. In an ore-classifying machine, the combination with an ore carrying table, a tank for containing fluid in which said table is adapted to be submerged, of a device for 40 oscillating said table relative to the tank, and means for controlling the oscillating impulses from said device in accordance with the movement of said table.

2. In an ore-classifying machine, the combination with a freely swingable ore carrying table, of a motor device actuated in accordance with the movement of the table for oscillating the table, the oscillating movement of said table being substantially 50 the same in each direction and substantially free from jolts and jars.

3. In an ore-classifying machine, the combination with a freely swingable ore carrying table, of a motor device actuated in accordance with the movement of the table for oscillating the table, the oscillating movement of said table being substantially the same in each direction and substantially free from jolts and jars, and means 55 for adjusting the amplitude of said motion.

4. A gravity ore-classifying machine comprising a liquid-containing tank, a uniformly oscillatable table mounted within the tank and partially submerged in said 65 liquid, a device for imparting uniform os-

cillating impulses to said table, the period of said impulses being controlled by the movement of said table, and means for governing the amplitude of said movement.

5. A gravity ore-classifying machine comprising a liquid-containing tank, an oscillatable table mounted within the tank and partially submerged in said liquid, a device for imparting uniform oscillating impulses to said table, said impulses being controlled by the movement of said table, and means for independently controlling the period and amplitude of said oscillation.

6. In an ore-classifying machine, the combination with a freely swingable table, of a device for uniformly oscillating said table, resilient means for mechanically connecting said device to said table, and means for controlling the impulses from said device in accordance with the movement of said table.

7. In an ore-classifying machine, the combination with a freely swingable ore-carrying table, of a spring having one end secured to a support and having the other end free to be moved from side to side, said table being mounted intermediate the ends of the spring, and means for swinging the free end of said spring to uniformly oscillate the table.

8. In an ore-classifying machine, the combination with a partially submerged ore-receiving table, and a hopper for supplying ore to said table, of a plurality of barriers disposed on edge and assembled in fan-like 100 formation adjacent the discharge opening of said hopper, said barriers being spaced from said table.

9. A gravity ore-classifying machine comprising a liquid-containing tank, an oscillatable table mounted within said tank and partially submerged in said liquid, an ore conveying belt mounted on said table and provided with a plurality of riffles, a hopper for supplying ore to said belt, means 105 for moving said belt continuously in a longitudinal direction, means for imparting lateral oscillations to said belt, and a plurality of longitudinally extending barriers disposed on edge and assembled in fan-like 110 formation from the point of discharge of said hopper, said barriers being adapted to oscillate with said table.

10. In an ore-classifying machine, the combination with an endless ore-carrying 120 belt, and means for moving the belt continuously in a longitudinal direction, of a plurality of barriers extending longitudinally of the belt, and means for laterally oscillating said barriers, said barriers being 125 mounted adjacent the surface of the belt.

11. In an ore-classifying machine, the combination with an ore-carrying member adapted to be uniformly oscillated laterally, of a plurality of barriers mounted above 130

- 6
- and extending longitudinally of said member, and means for laterally oscillating said barriers, said barriers being slightly removed from the surface of said member.
- 5 12. In an ore-classifying machine, the combination with an ore-carrying member adapted to be simultaneously moved in a longitudinal and in a lateral direction, of a plurality of longitudinal barriers adapted 10 to move only in a lateral direction and spaced adjacent the surface of said member.
13. In an ore-classifying machine, the combination with a liquid containing tank, and an ore-carrying member adapted to be 15 partially submerged in said tank, the surface of said member being provided with a plurality of riffles, of a device for longitudinally moving said member, a device for laterally oscillating said member, and a plurality of barriers separated from, and 20 mounted above, said member.
14. The combination with a freely swingable body, of a motor for uniformly oscillating said body, and resilient means connecting said motor to said body, means for 25 controlling the impulses from said motor in accordance with the movement of said body, the reversal of said motor being adapted to substantially precede each reversal of movement of said body in each direction.
15. The combination with a movable body and a device for moving said body, of a relay for controlling the operation of said device comprising a frame adapted to move in 30 accordance with the movement of said body, a pivotally mounted contact arm having limited movement, a contact member engaged by said arm, a part of said frame being adapted to frictionally engage said contact arm for actuating the same, a plurality 35 of stops adapted to move with said frame, a portion of said contact arm adapted to engage said stops for moving said arm in the opposite direction from said frictional movement.
16. The combination with a movable body, and a device for moving said body, of a relay for controlling the operation of said device comprising a slidably mounted frame 40 moved by said body, a plurality of stops secured to said frame, a contact member, a movable contact member adapted to engage said first contact member, a member connected to said frame for frictionally engaging said movable contact member for actuating the same, said movable contact member having means for engaging said stops for actuating said movable contact member against the frictional engagement of said 45 first-named member.
17. The combination with a contact member having a limited movement, of a moving part for actuating said member, said moving part being adapted to frictionally engage 50 said member for actuating the same, a plurality of stops on said moving part, said stops being adapted to engage said member to move the same in the opposite direction from said first-named movement.
18. The combination with a contact member having a limited movement, of a moving part for actuating said member, said moving part having substantially greater movement than said member, said moving part being adapted to frictionally engage 55 said member for actuating the same, a plurality of stops on said moving part, and resilient means for enabling said stops to yieldingly move said contact member in a direction opposite that of the moving part.
19. The combination with a stationary contact member, and a pivotally mounted contact arm, of a moving part for actuating said arm, a plurality of stops on said moving part, frictional means for engaging said arm, and resilient means secured to said arm for engaging said stops.
20. A relay comprising a movable member having a plurality of stops, a pivotally mounted contact arm, a member secured to 90 said arm and adapted to engage said stops, and a member connected to said movable member and adapted to frictionally engage said contact arm for actuating the same.
21. The combination with a freely swingable body, of a motor for uniformly swinging said body, means for yieldingly connecting said motor to said body, and mechanism for reversing the operation of said motor before the reversal of said body for each 100 swing of said body, the amplitude of movement of said body being adjustable.
22. The combination with a freely swingable body, of a motor for actuating said body, yielding means for connecting said 105 motor to said body, governing mechanism for controlling the operation of said motor in accordance with the movement of said body, the movement of said body and the impulse from said motor being materially out of phase, and means for adjusting the phase relation between the movement of said body and the impulses from said motor.
23. An ore-treating device comprising an ore-receiving table adapted to be partially submerged, and a plurality of relatively long flat barriers placed on edge and extending substantially parallel with the surface of said table and slightly spaced therefrom.
24. An ore-treating device comprising an oscillated table, and a plurality of relatively long narrow barriers spaced from and mounted on edge above said table, certain of said barriers being adapted to be oscillated with said table.
- In testimony whereof, I have hereunto subscribed my name this 12th day of Sept., 1917.
- 125
- WILLIAM C. McCOY.
